Mr J Hutchins

Inventor.

Samuel Shreffler Jr.

UNITED STATES PATENT OFFICE.

SAMUEL SHREFFLER, JR., OF JOLIET, ILLINOIS.

PARLOR-DOOR HANGER.

SPECIFICATION forming part of Letters Patent No. 256,247, dated April 11, 1882.

Application filed November 26, 1881. (No model.)

To all whom it may concern:

Be it known that I, SAMUEL SHREFFLER, Jr., of the city of Joliet, in Will county, and State of Illinois, have invented certain new and useful Improvements in Door-Hangers, the construction and operation of which I will proceed to explain, reference being had to the annexed drawings and the letters and figures thereon, in which—

10 Figure 1 is a side elevation of the hanger attached to the door; Fig. 2, a side elevation of the same detached from the door; and Fig. 3, a front elevation of the double-tread wheel of the hanger.

15 This invention relates to the construction and arrangement of the hanger to support the door and facilitate its movement, and is intended more particularly for parlor-doors or ordinary doors of a house, but may be used on 20 any door where it is practicable.

In the drawings, B represents the door, having a suitable hole or mortise in the top to receive the shank *z* of the hanger, and is held therein by the nut *n*, which operates in a mortise or recess in the side of the door, as shown 25 at *e*, Fig. 1, which opening may be closed by a suitable plate or cover. By means of the nut *n* the door may be regulated to cause it to hang plumb.

The shank *z* of the hanger is split in two parts or halves, so it will open to admit the axle of the wheel *s*. In Fig. 2 the dotted lines show it as it appears when open to receive the axle of the wheel. When the wheel *s* is in it appears as shown in Fig. 1. The upper part 35 of the hanger terminates in the part *w'*, having the long slot, in which the axle *s'* of the wheel *s* operates back and forth. The wheel *s* is intended to roll on a suitable track immediately over the door, as shown in Fig. 1 at *r*. 40

It is intended to place one of these hangers at each corner of the door; or any number may be used, as the size or weight of the door may require.

Having thus described my invention, what 45 I claim as new, and desire to secure by Letters Patent, is as follows, to wit:

The combination, with the wheel *s*, having two treads, and a central axle to support the hanger, of the hanger consisting of the slotted 50 upper end, *w'*, and split shank *z* and nut *n* to support the door *B*, in the manner and for the purpose set forth.

SAMUEL SHREFFLER, JR.
